ADJUSTABLE GROUND FITTING

Filed June 29, 1926

UNITED STATES PATENT OFFICE

HUDSON E. ZOGG, OF WARNERS, NEW YORK

ADJUSTABLE GROUND FITTING

Application filed June 29, 1926. Serial No. 119,303.

My invention has for its object an adjustable ground fitting having means for grounding an electric conductor passing through the conduit attached to said fitting, 5 to a water pipe or other ground, which is particularly simple and economical in construction and highly efficient and durable in use.

The invention consists in the novel features and in the combinations and constructions hereinafter set forth and claimed.

In describing this invention reference is had to the accompanying drawing in which like characters designate corresponding 15 parts in all the views.

Figure 1 is a vertical sectional view of my adjustable ground fitting, the contiguous portions of a conduit and a ground pipe being also shown.

Figure 2 is a plan view of parts seen in Figure 1.

Figure 3 is a sectional view taken on line 3-3, Fig. 2.

Figure 4 is a plan view partly broken 25 away of parts shown in Figure 2.

My invention comprises generally a member having a nipple at one end for connection to the conduit enclosing the ground wire, a member attachable to a ground pipe, 30 means for attaching the ground wire to said last mentioned member and lengthwise and radially adjustable means for connecting said members.

In connecting up a ground wire the wire 35 to be grounded is usually brought up to a water pipe or something similar, in a conduit and attached thereto to complete the circuit.

In so doing it is rather difficult to get the 40 enclosing conduit just the right length and properly aligned with the pipe to which it is to be connected.

In my ground fitting I have provided a 45 construction, whereby the fitting can be lengthened or shortened and one which can be adjusted radially if the conduit is not properly aligned with the ground pipe.

In the drawing the member 1 is provided 50 with a threaded nipple 2 for connection to the conduit as 3 enclosing the ground wire

4 which is to be connected in circuit with the ground, as for instance a water pipe or the like as illustrated at 5.

The member 1 as here shown is provided with a rectangular shaped opening 6 extending from the threaded nipple 2 through the other end of said member. This opening 6 preferably opens through the top of said member 1.

7 is a second member, one end of which is 60 preferably rectangular in general form, and provided with a seat 8 for the ground pipe 5, the other end 9 thereof being provided with an opening therethrough to be hereinafter described.

The member 7 as here shown is provided with a strap 10 having one end fixed thereto as by the rivet 11 and its other end provided with a series of spaced apart openings as 12.

13 is a third member one end of which is 70 rectangular in general form and slidably fitting the opening 6 in the member 1. This member is provided with a lengthwise slot 14 and a bolt 15 extends through said slot and threads into the bottom wall of the 75 member 1 thereby providing a lengthwise adjustment between the members 1 and 13. The other end of the member 13 is provided with an opening to be hereinafter described.

The ground wire 4 is provided with a clip 80 16 having an opening therein.

17 is a clamping member and 18 is a bolt.

In operation the member 1 is screwed to the conduit 3. The member 13 is adjusted to the desired length and the bolt 15 85 tightened.

The member 7 is then fixed to the ground pipe 5 with the seat 8 against said pipe and the strap 10 wound around as shown in Figures 1 and 2.

The bolt 18 is then placed through the opening in the clip 16. The clamping member 17 is then placed on the bolt and the bolt is put through one of the openings 12 in the free end of the strap 10, and through the opening in the end 9 of the member 7, the bolt is then screwed into the threaded opening in the front end of the member 13, thereby connecting all of said parts together.

This construction allows a radial adjustment between the members 13 and 7 as illustrated in Figure 4 as for instance when the conduit 3 is not at a right angle to the ground pipe as 5 to which it is to be connected.

What I claim is:—

1. An adjustable ground fitting comprising a member attachable to a conduit enclosing a ground wire, a member attachable to a ground pipe, means for attaching a ground wire to said last mentioned member means for connecting said members together, providing radial and lengthwise adjustments between said members comprising a member having one end thereof slidably connected to said first mentioned member by a slot and bolt construction, and its other end pivotally connected to said second mentioned member by a bolt.
2. An adjustable ground fitting comprising a member having a nipple at one end for connection to a conduit enclosing a ground wire and a rectangular passage extending from said nipple through the other end of said member, a second member having means thereon for attaching the same to a ground pipe, means for attaching the ground wire to said second member, means for obtaining a lengthwise adjustment and a radial adjustment between said members comprising a third member having one end thereof connected in the rectangular passage in said first mentioned member by a slot and bolt construction to said member to allow a lengthwise adjustment and having its other end connected to the second mentioned member by a bolt passing through said second mentioned member and threading into said last mentioned member to allow a radial adjustment, and means for maintaining said adjustments.
3. An adjustable ground fitting comprising a member attachable to a conduit enclosing a ground wire, a member having means fixed thereto for attaching the same to a ground pipe, said means comprising a strap for encircling said pipe having one end thereof fixed to said last mentioned member, a member having one end thereof connected by a lengthwise adjustable connection to said first mentioned member means for maintaining said adjustments, means for attaching the ground wire to said second mentioned member, and radially adjustable means for connecting said last mentioned member and said second mentioned member together comprising a bolt to which the ground wire is attached, said bolt passing through the free end of said strap through one end of said second mentioned member and threading into said last mentioned member.
4. An adjustable ground fitting comprising a member having a nipple at one end for

attaching the same to a conduit enclosing a ground wire, a second member having means thereon for clamping the same to a ground pipe, means for obtaining a radial and a lengthwise adjustable connection between said members comprising a third member having one end thereof slidably connected to the first mentioned member by a slot and bolt connection, and a bolt passing through one end of said second mentioned member, and threading into the other end of said third mentioned member, and means for connecting the ground wire to said bolt.

5. An adjustable ground fitting comprising a member having a nipple at one end thereof for attaching the same to a conduit enclosing a ground wire, a second member having one end of a strap fixed thereto for attaching the same to a ground pipe, a third member having one end thereof slidably connected to said first mentioned member to allow a lengthwise adjustment, and means for clamping the strap around the ground pipe, the ground wire to the strap and the second mentioned member to the third mentioned member.

6. A device for connecting an electric conductor and its enclosing conduit to a ground conductor comprising a coupling section having means for attachment to said conduit, a second coupling section adjustable lengthwise of and upon the first named section, a third coupling section pivotally mounted upon the second section for angular adjustment relatively thereto and provided with means for connections with the ground conductor and means for electrically connecting the electric conductor to said third section.

In testimony whereof, I have hereunto signed my name, at Syracuse, in the county of Onondaga, and State of New York, this 8th day of June, 1926.

HUDSON E. ZOGG.
